Charles Emmey, New York, N. Y.

Application August 26, 1937, Serial No. 71,341

Term of patent 14 years

To all whom it may concern:

Be it known that I, Charles Emmey, a citizen of the United States, residing in the city of New York and county of New York, State of New York, have invented a new, original, and ornamental Design for Embroidered Decorative Alphabet for Forming Monograms for Wearing Apparel or Similar Article, of which the following is a specification, reference being had to the accompanying drawing, forming part thereof.

In the drawing:

The figure is a plan view of the embroidered letters forming the present design.

The letters of the alphabet forming the present invention are of no appreciable thickness.

I claim:

The ornamental design for embroidered decorative alphabet for forming monograms for wearing apparel or similar article substantially as shown and described.

CHARLES EMMEY.
